UNITED STATES PATENT OFFICE.

ALPHONSO H. MARIETTA, OF AKRON, OHIO, ASSIGNOR TO THE GOODYEAR TIRE & RUBBER COMPANY, OF AKRON, OHIO, A CORPORATION OF OHIO.

BEAD-BUILDING MACHINE.

Application filed December 22, 1920. Serial No. 432,475.

My invention relates to bead building machines, and it has particular reference to machines for building composite bead rings of annular form.

5 The objects and advantages that may be derived from practicing my invention will be apparent from a study of the specification and the appended claims which constitute a portion of this application.

10 Like symbols of reference indicate like parts in each of the figures of the accompanying drawings;

Figure 1 of which is a side elevational view of a machine embodying my invention;

15 Figure 2 is an end elevational view, partially in section, of the bead-building portion of the unit shown in Figure 1;

Figure 3 is an end elevational view of the 20 fabric supply rack shown in Figure 1;

Figure 4 is a top plan view of the supply rack shown in Figure 3;

25 Figure 5 is an end elevational view of a fabric supply arm of the fabric supply rack shown in Figure 3;

Figures 6 and 7 are sectional elevational views taken substantially on lines 6-6 and 7-7 of Figure 4;

30 Figure 8 is an enlarged side elevational view partially in section, of one of the bead building tools applied to a partially formed bead ring;

Figure 9 is a sectional view of the bead form or mold and an accompanying partially formed bead ring contained therein and in the process of construction;

35 Figure 10 is a cross sectional view of a partially formed bead ring showing the elements entering into its assembly and their 40 relative positions;

Figure 11 is a sectional view of a completed bead ring; and

Fig. 12 is an enlarged fragmentary sectional view showing the application of the 45 positioning roller in the process of building a bead ring.

The machine for practicing my invention, which is shown in Figures 1 and 2 of the drawings, embodies a rotatable table 10 having a bead form or mold ring 11 mounted thereon to which the material for building the bead ring, which generally consists of a number of strands of steel wire, a filler material and a fabric covering, is 50 supplied from a supply rack 12. The ma-

terial thus supplied to the bead mold is subsequently molded by means of a positioning tool 13 and a shaping tool 14 that are mounted on a frame 15 which also supports the rotatable table 10. An electric 60 motor 16, or other suitable device, is adapted to drive the table 10.

Referring particularly to the frame and rotatable table construction, which is most clearly shown in Figure 1 and Figure 2 of 65 the drawings, the frame 15, which has a base member 18, rigidly supports an arbor 19 in a depending socket 20. The arbor 19 is rigidly secured in place by means of a lock nut 21.

The table 10 is rotatably mounted on the arbor 19 by means of interposed ball bearing raceways 22 and 23 that are accurately positioned and secured in place by means of an interposed sleeve 24 and a lock nut 25. 70 A master gear 26, which is secured to the hub portion of the table 10, is driven from the motor 16 through a motor pinion 27 and a gear train 28 which terminates in the driving pinion 29. A housing 30 encloses 75 the master gear 26 and the pinion 29. A dust ring 33 is secured to the rotatable table 10 to prevent dust and foreign material from entering the ball bearing raceways.

80 The mold ring 11, which has an angular molding groove 31 in its periphery, is removably secured to the rotatable table 10 by means of a series of dowel pins 32.

The arbor 19 also has a standard 85 secured thereto by means of a key 37 and a lock nut 38. The standard 90 support the shaping devices 13 and 14. The positioning device 13, which is shown most clearly in Figures 1 and 9, has a roll 39 rotatably mounted on one end of a pivoted arm 40, that is connected to a stationary bracket 41 by a bearing pin 41^a. A hand lever 42 provides means for moving the roll 39 into and out of engagement with the grooved mold ring 11. The positioning roll 39 has a pair of frusto-conical angularly related faces 39^a and 39^b that respectively correspond to the face of the molding groove and a radially extending annular shoulder 39^c for a purpose later to be described.

100 The general construction of the shaping device 14 is substantially the same as that of the device 13 with the exception of an auxiliary guide roll 45 and the shape of the periphery of the roll 46. The auxiliary 105

guide roll 45 is mounted on the supporting arm 47 off the shaping roll 46 by means of a bracket 48. The guide roll 45 is of frustoconical form and serves to present the strip 5 of steel reinforcing material to the shaping roll 46 at a proper angle.

The shaping roll 46, which is mounted on the arm 47, embodies a molding face 46^a, the elements of which are substantially parallel to the axis of the roll, and a pair of guide faces 46^b and 46^c that respectively engage the adjacent side walls of the molding groove when the roll 46 is moved to its operative position by the hand lever 49 as shown in Figures 1 and 2 of the drawings. A bearing pin 50 constitutes a support for the roll 46 and a bearing pin 51 serves as a mounting for the movable arm 47 on the stationary bracket 52. The described method of mounting the shaping devices 13 and 14 on the stand 36 insures the proper cooperation of the shaping rolls 39 and 46 with the molding groove when the rolls occupy their respective operative positions.

The operation of the motor 16 is controlled through the agency of a treadle switch 55, that governs the low speed operation of the motor, and a pair of push button switches 56 and 57 that are respectively adapted to control the starting and stopping of the high speed operation of the motor. The control switches 56 and 57 are enclosed in a housing 58 that is mounted on the stand 36 by means of a bracket 59. The conductors that connect the switches 56 and 57 with the motor control circuit, are led from the casing 58 of the push button switches through the conduit 61 to the main switches (not shown) for effecting the operation of the motor in accordance with conventional practice. The motor 16 is mounted on the base 18 in such manner as to be partially enclosed by the frame 15 which provides a compact and neat arrangement of the machine parts.

The supply rack 12, which is shown in Figures 1 to 7, inclusive, of the drawings, embodies a pair of supply rolls 70 and 71 that are removably mounted in brackets 72 and 73 and which respectively supply a fabric strip 74 and a metallic reinforcing strip 75 to the molding groove 31.

At take up roll 76 receives the cloth liner that is interposed between layers of the fabric strip 74 as it is unwound from the supply roll 70 and delivered to a fabric guide member 77, over an idler roll 78 that is rotatably mounted on a swingable arm 79. At bearing pin 80 serves to pivotally connect the arm 79 to the rack 12 in such manner as to permit the arm 79 to swing laterally a considerable degree. A guide bracket 81 on which the guide 77 is mounted, is adjustably secured to the arm 79 in such manner that it may be angularly adjusted rela-

tive to the arm 79. The bracket 81 has an adjustable stop 83 that engages the cylindrical side wall 84 of the rotatable table 10 to properly position the fabric supply guide 77 relative to the molding groove 31 of the mold ring 11 when the arm 79 occupies its operative position. The pivotal mounting of the arm 79 allows it to be swung away from the mold when not supplying material thereto.

The guide bracket 81 carries an angle arm 85 that supports a set of guide rolls 86 at its extremity which are held in place by means of a bolt 87. The set of guide rolls 86 serve to control the angle at which the reinforcing strip 75, which is of rectangular cross-section, is introduced into the molding groove 31 from the supply roll 71. A pair of frusto conical rolls 88 and 89 are mounted in inverted side-by-side relation. The roll 89 has a laterally extending annular flange 90 that defines an aperture between the rolls through which the reinforcing strip 75 extends in passing to the peripheral groove of the mold as illustrated in Figure 5 of the drawings. The bracket 85 and the supply guides 77 are secured in place by a pair of through bolts 91 and 92.

At take up roll 93 receives the cloth liner that is interposed between successive layers of the reinforcing strip 75 as it is unwound from the roll 71. A tension roll 94, over which the reinforcing strip 75 passes, has an adjustable tension device 95 of usual type employed in machines of this general character and a pawl and ratchet device 96 that permits of reverse movement of the roll 94 to adjust the tension of the strip 75 as it is supplied to the groove 31 of the molding 11. The strip 75 extends over an idler roll 97, that is most clearly shown in Figures 1 and 3 of the drawings, to the delivery rolls 86. The guide roll 97 is supported between parallel arms of a bracket 98 by means of a bearing pin 99. A guide block 100 bridges the arms of the bracket 98 to confine the reinforcing strip to the guide roll.

An auxiliary roll 101 is mounted on a laterally extending bearing pin 102 that is supported by a bracket 103 from the supply rack 12 and serves as a support for a roll of filler material 104 that is employed in the building of a bead ring.

The materials from which a preferred form of bead ring, which is shown in cross section in Figures 8 to 11 inclusive, of the drawings, may be constructed, includes the fabric strip 74, the reinforcing strips 75 and the strips of filler material 104. The fabric strip 74 is a suitable width of cloth that has been calendered to impregnate it with rubber in a manner familiar to those skilled in the art. This fabric strip constitutes the covering for the bead ring. The reinforcing strip 75 is composed of loosely braided strands 130

of steel wire, which, in their assembled form, are thoroughly impregnated with rubber. This reinforcing element is of rectangular cross section as shown in the drawings. The 5 filler material 104 is of any desirable rubber composition which may be employed in the construction of the ring.

The operation of my device takes place substantially as follows: Rolls 70 and 71 of 10 suitable fabric 74 and reinforcing material 75 are placed in the brackets 72 and 73 of the supply rack 12 and the strip of fabric 74 is led over the take up roll 76 to which the cloth liner for the fabric strip 74 is attached, over the idler roll 78 and through the 15 fabric guide 77 to the molding groove 31. The reinforcing element 75 is led over the take up roll 93 to which the cloth liner is attached over the tension roll 94 which is 20 adjusted to impose the proper tension on the reinforcing strip, over the idler roll 97 and between guide rolls 88 and 89 to the mold groove.

The operator now treats the molding 25 groove 31 and its adjacent faces with rubber cement, or other substance that insures proper adhesion of the fabric strip with the surface of the molding groove, places the end of the fabric strip 74 in proper position 30 relative to the molding groove 31 and effects the rotation of the mold ring 11 by depressing the foot treadle 55. When a complete layer of fabric is wound on the mold ring the fabric is severed and the ends joined in such 35 manner that the end of the strip initially secured to the ring 11 becomes the uppermost end of the overlapped ends of the fabric strip.

The end of the reinforcing element 75 is 40 wound with a narrow strip of tape, or other material, to prevent the unraveling of the steel wire strands and to insure their proper engagement with the fabric strip. The mold is again rotated by the depression of 45 the treadle switch 55 and two layers of the reinforcing element 75 are forced into engagement with the vertical molding surface of the groove 31 by pressure on the hand lever 42. This forces the positioning roll 39 into operative position with reference to the 50 molding groove. The annular flange 39^c of the roll 39 engages the uppermost edge of the reinforcing strip as it is introduced from the guide rolls 86 into the molding groove in angular relation to the molding 55 face to insure the proper positioning of the strip in the groove by downward pressure from the flange 39^c and lateral pressure from the roll face 39^b. This relation is clearly 60 shown in Figure 12.

Since the reinforcing element 75 is quite pliable, and since it is also impregnated with uncured rubber gum that is very tacky, it must be placed exactly where it belongs immediately upon its introduction into the

groove. By introducing the element 75 at an angle to the face of the mold, the lowermost inside edge first engages the inside corner of the mold. The operation of the roll 39 forces the strip securely into the corner of the mold and then lays the strip against the side of the groove. In this way, the strip is positioned without the necessity of sliding the strip along the fabric 74 or wrinkling the fabric in an effort to properly 70 position the strip after it is in engagement therewith. It is also very difficult to obtain a secure seating of the top flange 39^c of the roll on the top of the strip, if the face of the reinforcing strip is parallel with the face 75 39^b of the roll.

When two layers of the reinforcing elements 75 are wound on the molding ring 11, a narrow strip of tape is wound about the reinforcing element 75 which is then severed at the point where the tape is located to prevent unraveling of the wire strands and the mold is again rotated with the roll 39 firmly pressed against the two layers of reinforcing element as shown in Figure 8 of the 80 drawings.

Two layers of filler material 104 of different widths are now wound along the bottom edge of the strips of reinforcing material and a final layer of the reinforcing strip 75 is wound in angular relation to the filler strips and the previously applied reinforcing strips, as shown in Figure 10. The last mentioned layer of reinforcing element 90 is wound into proper relation with the previously applied elements by means of the auxiliary roll 45 which introduces the reinforcing strip at a desirable angle to the shaping roll 46. The bead ring is formed to the contour of the molding groove by 95 means of the roll 46 to which pressure is applied through the hand lever 49. The guide faces 46^b and 46^c of the roll 46 insure proper 100 size of cross section of the bead ring so built up, and also properly position the final layer 105 of reinforcing element that is introduced into the molding groove. The manner of engagement of the guide faces of the roll with the mold groove is clearly illustrated 110 in Figure 2 of the drawings.

The mold ring is now rotated at its high speed by depression of the push button switch 56 and the edges of the fabric strip 74 are successively folded over the assembled reinforcing and filler elements by the use of 115 suitable hand tools such as are employed by those skilled in the art in similar operations. The bead ring so assembled is now finally formed and sized by proper pressure on the roll 46 prior to its removal from the molding groove 31. This latter operation may be accomplished by inserting a stitching wheel or knife (not shown) beneath the 120 fabric of the bead ring, to lift it from the groove. 125

The semi or complete vulcanization of the bead ring thus constructed finishes the bead ring and prepares the same for use in the manufacture of tire casings.

It will be obvious that the arrangement and relation of parts in the machine herein disclosed may be altered without departing from the spirit and scope of my invention and I desire therefore that only such limitations shall be imposed as are indicated in the accompanying claims.

What I claim is:

1. A machine for building bead rings comprising a rotatable and peripherally grooved form adapted to receive the component elements of the bead ring, a roll adapted to swing laterally relative to said groove to operative relation with the peripheral groove, said roll having a flanged periphery adapted to position the material introduced into the peripheral groove of the mold, and a guide adapted to direct the component elements of the bead ring between the roll and the form, said guide being swingable toward and away from said form.

2. A machine for building bead rings comprising a rotatable table, a peripherally grooved mold mounted thereon and rotated thereby, means for introducing a component element of the bead ring in angular relation to the molding groove, a shaping roll mounted in definite operative relation with the peripheral groove and adapted to engage and position the introduced element in parallel relation with the sidewall of the groove.

3. A machine for building bead rings comprising a rotatable table, a peripherally grooved mold mounted thereon and rotated thereby, a stitching roll mounted in definite operative relation with the peripheral groove, a device for supplying material to the molding cavity, and adjustable means for operatively positioning said device relative to the molding cavity.

4. A machine for building bead rings comprising a rotatable table, a peripherally grooved mold mounted thereon and rotated thereby, a shaping tool mounted in definite operative relation with the peripheral groove and adapted to cooperate therewith, a device for supplying material to the peripheral groove, and adjustable means engaging the periphery of the mold for maintaining the supply device in proper operative relation to the mold.

5. A machine for building bead rings comprising a rotatable table, a peripherally grooved mold mounted thereon and rotated thereby, a shaping tool mounted in definite operative relation with the peripheral groove and adapted to cooperate therewith,

a pivotally mounted arm adapted to guide material supplied to the groove, a guide member mounted on the extremity of said arm, means for angularly adjusting the guide member relative to the pivotal arm, and means adapted to engage the periphery of said mold for adjusting the relation between the guide member and said mold.

6. A machine for building annular rings which comprises a revoluble form having a peripheral groove, means for supplying a flat strip of material to the form, a tool carried by a stationary part of the machine and manually movable into operative engagement with the mold, said tool being adapted to simultaneously arrange the strip of material within the mold and to apply molding pressure thereto and a second tool similarly mounted and adapted to shape the material and to apply molding pressure thereto, said tools being adapted to be used in a prearranged order.

7. A machine for building bead rings comprising a rotatable member having a peripheral groove corresponding in profile to two sides of a bead ring, means for rotating the member, means for supplying respectively a metallic reinforcing element, a strip of filler material and a strip of fabric used in the building of said bead, and a guide arm swingable into and out of operative relation with said rotatable member, a roller adapted to press the component elements of said bead rings into the peripheral groove of said rotatable member; said guide having independent means for respectively directing said reinforcing element and said fabric strip between the rotatable member and said roller.

8. A machine for building bead rings comprising a rotatable member having a peripheral groove corresponding in profile to two sides of a bead, means for rotating said member, a positioning roller adapted to position each component part of said bead in definite relation to the remaining parts of said bead, and a finishing roller of materially different contour adapted to finish the outer surface of the said bead.

9. A machine for building bead rings comprising a rotatable member adapted to receive a bead reinforcing strip and having a peripheral face corresponding in profile to the inside face of the bead ring, means for supporting and rotating said member, and means adapted to position said reinforcing strip laterally of the rotatable member.

In witness whereof, I have hereunto signed my name.

ALPHONSO H. MARIETTA.
